[57] CLAIM

The ornamental design for a hot box detector scanner
housing, as shown and described.

DESCRIPTION

FIG. 1 is a top plan view of a hot box detector scanning
housing showing my new design;

FIG. 2 is a left side elevational view, the right side
elevational view being identical;

FIG. 3 is a bottom plan view;

FIG. 4 is a front elevational view; and

FIG. 5 is a rear elevational view thereof.
